UNITED STATES PATENT OFFICE.

FREDERICK SIEVERS AND WILLIAM HILDEBRAND, OF FORT WAYNE, IND.

IMPROVEMENT IN RUFFLING OR PLAITING ATTACHMENTS FOR SEWING-MACHINES.

Specification forming part of Letters Patent No. 152,254, dated June 23, 1874; application filed June 5, 1874.

To all whom it may concern:

Be it known that we, FREDERICK SIEVERS and WILLIAM HILDEBRAND, of Fort Wayne, in the county of Allen and State of Indiana, have invented certain new and useful Improvements in Ruffling or Plaiting Attachments for Sewing-Machines; and we do hereby declare that the following is a full and exact description thereof, reference being had to the accompanying drawings, and to the letters of reference marked thereon, in which like letters refer to like parts in the different figures.

To enable others skilled in the arts to make and use our invention, we will proceed to describe its construction and operation.

In the drawings, Figure 1 is a side elevation. Fig. 2 is a plan view. Fig. 3 is a side elevation.

The nature of our invention consists in the construction and operation of an apparatus to be used for the purpose of forming plaits in cloth, and presenting them in such a manner that they may be stitched separately or to another piece of cloth, said apparatus forming an attachment to a sewing-machine.

In the drawings, A represents a reciprocating bar, which is supported by means of suitable ways, in which it moves. Said ways a are formed on clamps B. Bar A is provided on its upper surface with teeth, into which pawls b and c take. Said pawl b is actuated by arm d, which is pivoted to rock-shaft g. Pawl c is secured to and actuated by arm h, which is also secured to rock-shaft g. When motion is imparted to rock-shaft g, said pawls are alternately forced in opposite directions. C represents an oscillating lever, which is secured to a vibrating arm, i, pivoted, as seen at k, at its center, and on its lower edge is formed a V-shaped projection, m, which operates upon one of like form on the upper surface of spring l. When said bar C oscillates said projection m presses said spring downward, and passes over projection m' thereon. D represents a stop, which is formed on reciprocating bar A, and presents an inclined surface to the inclined surface on the end of oscillating bar C. E represents an adjustable stop, which is also provided with an inclined surface, which acts upon a like surface

on the adjacent end of bar C. When rock-shaft g is operated, movement is imparted to bar A through one of the pawls, the other, at the time, being disengaged by the oscillating bar C. Thus said bar A is carried forward until stop D impinges the inclined surface of bar C, and forces it downward, and at the same time carries projection m over projection m' on spring l. The opposite end of said bar is thus elevated, and the pawl is disengaged. At the same time the opposite pawl engages the ratchet, and the movement of the bar is reversed, and is carried back to the stop on the opposite end, where a like result is produced. Thus an intermittent reciprocating motion is produced; but it is necessary, in order to produce the desired effect, that the outward movement of the bar A be much slower than the return movement. This end is attained by securing the pawl to an arm having a shorter stroke than that to which the other is secured. It is also necessary that the length of the stroke should be made adjustable for the purpose of increasing or diminishing the fullness of the plaits. This object is attained by pivoting a recessed arm, n, on a line with rock-shaft g; to its lower end pawl C is attached. Arm h is slotted so as to admit an adjustable pin, O, which passes through recessed arm d. Said recess is V-shaped, as seen in the drawings in dotted lines. Any change of position of pin O causes a corresponding change in the length of said arm, thus increasing or decreasing the fullness of the plaits. H represents a stationary bar, which is secured to clamp B by any suitable means. Said bar is made thin and flexible, and is so placed that its inner end extends nearly to the needle under the foot-piece l, which is also secured to said clamp. J represents a plait-folder, which is secured to bar A, and reciprocates with it. Said folder rests on or immediately above bar H.

When cloth is to be plaited and stitched to another piece, that to be stitched to the plaits is placed under bar H in the usual manner, while that to be plaited is placed between bar H and plait-folder J, so as to extend under foot-piece l. The reciprocating motion of plait-folder J forms the plaits, and presents them to the needle, when they are stitched to

the under cloth. When plaits are to be made singly the cloth is inserted as before, omitting the under cloth.

What we claim as new, and desire to secure by Letters Patent, is—

1. Arm *d*, pawl *b*, arm *k*, and pawl *c*, each constructed and operating in the manner and for the purpose substantially as described.

2. Oscillating bar *C*, stop *D*, adjustable stop

E, and spring *l*, each being constructed as described, for the purpose of alternately disengaging pawls *b* and *c* from ratchet-bar *A*, and thus reversing its motion.

FREDERICK SIEVERS.
WM. HILDEBRAND.
